UNITED STATES PATENT OFFICE.

JACOB J. BYERS, OF CHICAGO, ILLINOIS, ASSIGNOR TO THE NATIONAL MALLEABLE CASTINGS COMPANY, OF CLEVELAND, OHIO, A CORPORATION OF OHIO.

RAIL-ANCHOR.

1,032,349.

Specification of Letters Patent.

Patented July 9, 1912.

Application filed January 3, 1912. Serial No. 669,201.

To all whom it may concern:

Be it known that I, JACOB J. BYERS, a resident of Chicago, in the county of Cook and State of Illinois, have invented a new and useful Improvement in Rail-Anchors, of which the following is a full, clear, and exact description, reference being had to the accompanying drawings, forming part of this specification, in which—

6 Fig. 1 is a sectional end elevation of a rail anchor embodying my invention, the section being taken on the line I—I of Fig. 3; Fig. 2 is a side elevation showing the anchor in position; Fig. 3 is a top plan view 5 of the anchor; Fig. 4 is a detail view showing in elevation one of the anchor castings; Fig. 5 is a top plan view; Fig. 6 is a bottom plan view of the same; and Figs. 7 and 8 are views of a modified form employed in 10 connection with the tie-plate.

My invention relates to rail anchors of the type set forth in my United States Letters Patent No. 978,110, granted on December 6, 1910, for improvement in rail anchors, and 15 is designed to improve this type of anchor.

Among the objects of my invention are to strengthen the gripping action, to do away with the insert, to enable the cores to be duplicates for both halves of the plate, and to 20 make the two halves as substantial duplicates of each other, if desired, except for the tie-engaging projection or projections where these are used.

In the drawings, referring to the form of 5 Figs. 1 to 6 inclusive, 2 represents the rail, 3 the cross tie, the anchor being made in two parts 4 and 5, which are substantial duplicates of each other, except that the stationary member 4 is provided with the depending projection or projections 11. Each half or member of the anchor has at one of its longitudinal edges an overhanging inwardly curved abutment 6, and at its other end an inwardly projecting overhanging lip 7, these 10 being inclined or tapered longitudinally, so that when reversed in position, the overhanging lip of one member will have a wedging engagement inside the overhanging abutment of the other member. The web 15 portion 9 of the section upon which the rail seats is diagonally cut away, as shown at 10, so that when the two sections are applied to each other, the upper portions of the web together constitute the seat for the rail, while 15 the overhanging lip of each section engages the

overhanging abutment of the other section. In order to strengthen the sections while at the same time making them as light as possible, I provide each member with a diagonal depending bottom lip 12, extending from one corner to the other and merging into one of the flanges 13, which back up and strengthen the overhanging abutment. One of these flanges 13 may be used for driving the device home and this flange is preferably provided with a backing-up rib 14, which may also be present on the other member, if desired. The member having the projections 11 is substantially the same as the other section, except that one of these projections 11 65 may have the rib extension 15 running across the bottom of this member to the diagonal depending ribs 12. A depending rib 16 extends along one edge of each member 4, being, of course, on the side having the depending projections, where such are used. 70 In order to make the web of substantially the same thickness throughout, depressions 17 are formed in the bottom portions, 75 matching with the raised portions forming the rail seats. The recesses in the overhanging lips which engage the rail base are preferably proportioned so that the base flange of the rail will be gripped between the inclined upper surfaces 18 and the lower surface 19, whether the edge of the base flange of the rail is engaged or not. I preferably proportion these recesses so that the rail will 80 be engaged both on the top, bottom and edge of this base flange when the anchor is driven 85 completely home.

In Figs. 7 and 8, I show a form of the invention similar to that of Figs. 1 to 6, inclusive, except that the anchor in this form is designed to be used with a tie-plate 20, which is shaped so as to form an abutment against which the body of one of the members will abut. In this case, therefore, the tie-engaging projection or projections is done away with, and the members are preferably exact duplicates of each other. In 90 these figures, parts similar to those of Figs. 1 to 6, inclusive, are indicated by similar numerals with the letter "a" applied.

The advantages of my invention will be 95 apparent to those skilled in the art, since the anticreeper or rail anchor of the general type shown in my prior patent is made stronger and simpler. The cores may be duplicates for both castings and the castings 100 110

are duplicates, except for the rail-engaging projection or projections. The manufacture of the device is somewhat cheapened, it is made as light as consistent with proper strength in malleable castings, and if the rail moves back from the tie, the device is not liable to drop off, inasmuch as the parts will be carried along as a whole. This is due to the fact that each lip is wedged between the rail and backing-up abutment of the mate castings.

Changes may be made in the form and arrangement of the parts, without departing from my invention.

15. I claim:

1. A rail anchor comprising two parts or members having longitudinal wedging engagement with each other at each side of the rail base and arranged to grip the base 20 of the rail, each section having at one side an overhanging lip having engagement with the base flange of the rail and at the opposite side an overhanging flange, the lip of one section having wedging engagement 25 with the abutment of the reverse section, substantially as described.

2. A rail anchor composed of two parts which are substantial duplicates of each other, except for the tie-engaging projections of the stationary part, each of said parts having at one side an overhanging rib and at the other side an overhanging abutment, the lip of one member having a wedging engagement with the abutment of 35 the other member, substantially as described.

3. A rail anchor comprising two parts or members, each having an overhanging rail-engaging lip at one side and an abutment at the other side, the lip of each member being arranged to be wedged between the rail base and the abutment of the other member, the lip being formed to grip the base flange of the rail on its top and bottom surfaces, substantially as described.

45. 4. A rail anchor composed of substantially duplicate parts, each part having an overhanging lip along one side and an overhanging abutment along the other side, the overhanging lip of one member being arranged 50 to be wedged between the abutment of the other member and the rail base, each member having the bottom recessed upwardly moving depending strengthening rib, substantially as described.

55. 5. A rail anchor composed of substantially duplicate parts, each part having an overhanging lip along one side and an overhanging abutment along the other side, the overhanging lip of one member being arranged 60 to be wedged between the abutment of the other member and the rail base, each

member having the bottom-recessed upwardly-moving depending strengthening ribs, and each member having a web portion of substantially the same thickness throughout, substantially as described.

6. A rail anchor composed of two substantially duplicate parts, each having at one edge an overhanging rail-engaging lip and at the other edge an overhanging abutment, the lip of one member being arranged to be wedged between the abutment of the other member and the base flange of the rail, the web portion of each member having a depressed floor portion to receive the web 75 of the other member, substantially as described.

7. A rail anchor composed of two substantially duplicate parts, each having at one edge an overhanging rail-engaging lip 80 and at the other edge an overhanging abutment, the lip of one member being arranged to be wedged between the abutment of the other member and the base flange of the rail, the web portion of each member having a 85 depressed floor portion to receive the web of the other member, the overhanging abutment having projecting reinforcing ribs, substantially as described.

8. A rail anchor composed of two substantially duplicate parts, each having at one edge an overhanging rail-engaging lip and at the other edge an overhanging abutment, the lip of one member being arranged to be wedged between the abutment of the other member and the base flange of the rail, the web portion of each member having a 90 depressed floor portion to receive the web of the other member, each member having depending bottom ribs extending to and forming strengthening ribs for the overhanging flange, substantially as described.

9. A rail anchor composed of two substantially duplicate parts, each having at one edge an overhanging rail-engaging lip 95 and at the other edge an overhanging abutment, the lip of one member being arranged to be wedged between the abutment of the other member and the base flange of the rail, the web portion of each member having a 100 depressed floor portion to receive the web of the other member, each member having a depending flange along one edge and a diagonal depending flange extending across the bottom, said flanges forming backing-up lips 105 for the abutment, substantially as described.

In testimony whereof, I have hereunto set my hand.

JACOB J. BYERS.
